Primary Examiner — Dana K Weiland*Assistant Examiner* — Kathryn Elizabeth Zieno(74) *Attorney, Agent, or Firm* — Tommy SF Wang; Wang IP Law Group, P.C.(57) **CLAIM**

The ornamental design for a toilet as shown and described.

DESCRIPTION

FIG. 1 is a front perspective view of a toilet showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an alternate front perspective view thereof.

The translucent rod structure across the top surface of the tank depicts the lighting strip. The broken lines in FIGS. 1-8 illustrate portions of the toilet that form no part of the claimed design. The dot-dash broken lines in FIGS. 1-5, and 7-8 depict boundaries of the claim and form no part thereof.
